(57) **CLAIM**

The ornamental design for an electrical connector, as shown and described.

DESCRIPTION

FIG. 1 is a bottom-front-right perspective view of a first embodiment of an electrical connector showing our new design;

FIG. 2 is a top-front-left perspective view thereof;

FIG. 3 is a top plan view thereof;

FIG. 4 is a bottom plan view thereof;

FIG. 5 is a left side elevation thereof;

FIG. 6 is a right side elevation thereof;

FIG. 7 is a front elevation thereof;

FIG. 8 is a rear elevation thereof;

FIG. 9 is a top-front-right perspective view of a second embodiment of an electrical connector showing our new design;

FIG. 10 is a bottom-front-left perspective view thereof;

FIG. 11 is a top plan view thereof;

FIG. 12 is a bottom plan view thereof;

FIG. 13 is a left side elevation thereof;

FIG. 14 is a right side elevation thereof;

FIG. 15 is a front elevation thereof;

FIG. 16 is a rear elevation thereof;

FIG. 17 is a top-front-right perspective view of a third embodiment of an electrical connector showing our new design;

FIG. 18 is a bottom-front-left perspective view thereof;

FIG. 19 is a top plan view thereof;

FIG. 20 is a bottom plan view thereof;

FIG. 21 is a left side elevation thereof;

FIG. 22 is a right side elevation thereof;

FIG. 23 is a front elevation thereof; and,

FIG. 24 is a rear elevation thereof.

In the drawings, the broken lines represent portions of the article that form no part of the claimed design.

1 Claim, 6 Drawing Sheets

Related U.S. Application Data

continuation-in-part of application No. 29/607,301, filed on Jun. 12, 2017, now Pat. No. Des. 890,098.
